UNITED STATES PATENT OFFICE.

GEORGE C. VENNUM, OF WESTFIELD, NEW JERSEY, AND HENRY B. BRADFORD, OF EDGE MOOR, BRANDYWINE HUNDRED, DELAWARE, ASSIGNEES TO EDGE MOOR IRON COMPANY, OF EDGE MOOR, DELAWARE, A CORPORATION OF DELAWARE.

STEAM SUPERHEATER.

Application filed February 16, 1922. Serial No. 536,901.

To all whom it may concern:

Be it known that we, GEORGE C. VENNUM, a citizen of the United States of America, and resident of Westfield, county of Union, 5 State of New Jersey, and HENRY B. BRADFORD, a citizen of the United States of America, and resident of Edge Moor, Brandywine Hundred, county of New Castle, State of Delaware, have invented certain new and 10 useful Improvements in Steam Superheaters, of which the following is a true and exact description, reference being had to the accompanying drawings, which form a part thereof.

15 Our invention relates to steam superheaters and has for its object to provide a superheater which in its construction and in the way in which it is secured in place in the boiler is especially well adapted both to perform its function of superheating steam and 20 also to withstand without injury the internal strains to which it is subjected by varying temperatures. A further and particularly important object of our invention is to 25 provide a superheater especially well adapted to operate in such a way that the steam superheated in it can be delivered at a practically constant temperature.

30 The nature of our improvements will be best understood as described in connection with the drawings in which they are illustrated in connection with a boiler invented by George C. Venum and for which he has filed an application for Letters Patent 35 bearing the Serial No. 482,086, for the reason that our improved superheater is especially well adapted for use in connection with the Venum boiler.

In the drawings:

40 Figure 1 is a sectional side elevation of the Venum boiler with our improved superheater shown in position therein.

45 Figure 2 is a plan view of the boiler and superheater shown in Fig. 1 with the boiler casing removed and the upper front drum shown partly in section, the other rear drum and its connections partly cut away and with the roof of the fire box partly removed.

50 Figure 3 is a cross sectional view taken as on the line 3—3 of Fig. 1, showing the superheater in front elevation.

55 Figure 4 is a plan view of the superheater together with a diagrammatic showing of the electro-mechanical mechanism provided

for automatically operating the dampers of the superheater, and

Figure 5 is an end elevation of the superheater with its connections as shown in Figs. 3 and 4 and with the headers to which the superheated tubes are connected shown in section.

A is the fire box of the boiler opening into a large combustion chamber indicated at A' which in turn connects with chamber A² through the tubes of the boiler. B is 65 the bottom drum of the boiler; B' and B² the upper drums. The drums B and B' are connected by a tube bank indicated at C. The upper drums B' and B² are connected through the pipes indicated at C' and the 70 drums B² and B are connected by circulation tubes indicated at C². D is the rear chamber of the boiler enclosed between converging walls indicated at D', D', and opening to the stack or take-off flues through the 75 passage indicated at D². E, E², and E⁴ indicate three groups of headers connected together by tubes as indicated at F and located at the top of the chamber D, these 80 headers being connected with the groups of headers E³, E' and E⁵ located at the bottom of the chamber D through tube groups indicated at F', F² and F³. G indicates the pipe and valve system by which water is fed to the headers indicated at E, E² and 85 E⁴. H, H, etc. are tubes connecting the header group E⁴ with the drum B². I are steam take-off pipes connected with the header group E⁴ and opening into a header I' which communicates with the steam 90 space of the drum B² through pipes indicated at I².

In all the features briefly noted above the boiler shown in our drawings is the Venum boiler which forms in itself no part of 95 our present invention.

J indicates our improved superheater made up, as shown, of a header J' which is connected to the steam space of the drum B² through pipes indicated at M. The header 100 J' is connected to the bottom header indicated at J² by groups of tubes indicated at K so disposed as to leave openings indicated at L, L, between the groups of tubes. The header J² is connected to a header J³ 105 by short tubes, as shown, these two headers forming practically one header and the third bottom header J³ is in turn connected

with an upper header indicated at J^4 by groups of tubes indicated at K' similarly disposed to the two groups indicated at K so as to secure open spaces L , L , extending 5 through the tubes. The header J^4 connects at its ends, indicated at J^5 , J^5 , to the take-off conduit for superheated steam. The header J' is supported from the top of the 10 boiler housing on stirrups indicated at N , N , and the header J^4 is similarly supported on stirrups indicated at N' , N' , in which are interposed springs indicated at N^2 , N^2 , which tend to draw the supporting part of the stirrup upward so that the stirrups will 15 continue to perform their supporting function even if the tube groups K' should be elongated by heating to a greater extent than the tube groups K .

O , O , are dampers secured to rotatable 20 shafts indicated at O' , O^2 , which move in bearings O^3 , O^3 , secured to the headers, as shown in Fig. 3, the dampers being so placed and proportioned as to close the open 25 passages L in one position and to leave these passages practically open when turned through an angle of 90° . The upper rotatable shafts O' are, as shown, supported by chains indicated at P and a chain or other easily twistable support is highly desirable 30 as a means of supporting the dampers in place. To the bottoms of the lower shafts O^2 are secured crank arms indicated at Q , Q , which are in turn secured to a damper actuating rod indicated at R and having, as 35 indicated at R' a limit stop secured to its outer end. S , see Fig. 4, is a worm wheel to which is secured a crank arm S' connected to the damper rod R . The worm wheel S is actuated through a worm T secured on the shaft T' to which is also secured the large gear wheel T^2 engaged by the small gear T^3 of the shaft T^4 of a reversing electric motor indicated at T^5 , T^6 indicating an electric brake on the shaft T^4 . 40 X is a thermostat located, as shown, at the outlet of the header J^5 and connected to actuate a two point switch indicated at V . The wiring of the motor is of the usual character of the reversing motor and in the 45 circuit wires, as indicated, the wire W leads to the switch V and through the switch in one of its extreme positions current passes from the wire W' to a limit switch indicated at U and when this switch is closed 50 through a wire W^2 to one of the wirings of the motor. In the other position of the two point switch V the current passes from the wire W to the wire W^3 and thence to a limit switch U' and when this switch is 55 closed through the wire W^4 to the other wiring of the motor. The current through either motor winding passes through the wire W^5 through the electric break indicated at T^6 and thence through the wiring indicated at W^6 .

In operation the superheater constructed as described is located immediately in the rear of the headers B , B^2 , and directly across and so as to entirely fill the space for the boiler gases by which the gases from the 70 chamber A^2 pass to the chamber D and it will be observed that when the dampers O are closed as indicated in Figs. 3 and 4, all of the gases pass through the tube groups of the superheater which are preferably staggered, as indicated in Fig. 4, and which in this position of the dampers receive the maximum amount of heat from the boiler gases and secure, of course the maximum superheating of the steam. Again, it will 75 be obvious that when the dampers O are partly or wholly open a large portion of the gas from the chamber A^2 will pass to the chamber D of the boiler without passing through the tubes of the superheating 80 groups but whatever increased heat of the boiler gases is thus passed through the superheater without utilization is fully utilized by the boiler tubes in the chamber 85 D .

It is, of course, advisable that the position of the dampers in the superheater should be controlled and regulated by the temperature of the steam as it issues from the superheater. This could be accomplished in many ways and, as shown, we effect this control by means of a thermostat indicated at X which connects the circuit wire W either with the circuit wire W' or the circuit wire W^3 as the temperature 90 of the superheated steam rises or falls between certain points and thus energizes the motor alternately in opposite directions. The rotation of the motor through the gears indicated and described communicates 95 a slow and gradual motion to the worm wheel S and through the crank arm S' to the damper rod R and to the dampers. The limit stop R' on the damper rod opens one or the other of the limit switches U or U' in the position of the rod in which the damper is fully closed or fully opened, thus cutting off the current to the motor. To insure that the motion of the dampers shall be promptly arrested when the motor 100 circuits are opened as above described we prefer to employ an electrically operated stop such as a brake. This can be located in any convenient place and, as shown, we provide a brake T^7 acting on a brake drum on the motor shaft which so long as a circuit is passing through the motor is non-operative but which acts to arrest the motion of the shaft and connected parts as soon as current ceases to flow through the 105 motor.

By sustaining the superheater in position and sustaining also the dampers O , O , in a vertical position the distortion of the superheater and dampers from the effect of 110

changing temperatures is minimized and by constructing the superheater with its upper header secured in position and its lower header or headers free to move, distortion and strains due to temperature variation are minimized while, as we have pointed out, the use of springs in the hangers of the headers J' also compensates for the effect of varying temperature and maintains proper support for the header J' even although its tubes be disproportionately longer with reference to the tube groups K^1 .

Having now described our invention, what we claim as new and desire to secure by Letters Patent, is:

1. In combination with a steam boiler having a contracting gas pass through which the heating gases pass, a wide and comparatively shallow superheater made up of substantially straight tubes connected at their ends to headers, said superheater being located in and extending substantially across the full width and height of said gas pass, and having its tubes arranged in groups with an open space or spaces between said groups, and one or more dampers located in said open spaces, whereby said spaces can be regulated in area.

2. In combination with a steam boiler having a horizontal contracting gas pass through which the heating gases pass, a vertically extending wide and comparatively shallow superheater located in and extending substantially across the full width and height of said gas pass and having its tubes arranged in vertical groups with an

open vertical space or spaces between said groups and vertical dampers located in said open spaces.

3. A wide and comparatively shallow superheater made up of groups of substantially parallel vertical tubes with free vertical spaces between said groups; the tubes being held in remotely placed headers in which the headers at the top of the tubes are adapted to be connected to the steam inlet and outlet connections and the bottom headers are free to move, in combination with vertical dampers located in said free spaces whereby they can be closed or regulated for the passage of gases.

4. In combination with a steam boiler having a horizontal gas pass through which the heating gases pass, a vertically extending superheater located in and substantially filling said gas pass and having its tubes arranged in groups with an open space or spaces between said groups and dampers located in said open spaces and suspended in place therein by freely twistable supports.

5. A superheater made up of substantially parallel tubes connected at their tops to separate inlet and outlet headers and at bottom to a common header free to move with a reference to the top headers in combination with means for supporting the inlet header and resilient means for independently supporting the outlet header.

GEORGE C. VENNUM.
HENRY B. BRADFORD.
